UNITED STATES PATENT OFFICE.

EDWARD E. HENDERSON, OF SANFORD, FLORIDA.

WAGON RUNNING-GEAR.

SPECIFICATION forming part of Letters Patent No. 508,420, dated November 14, 1893.

Application filed June 24, 1893. Serial No. 478,706. (No model.)

To all whom it may concern:

Be it known that I, EDWARD E. HENDERSON, a citizen of the United States, residing at Sanford, in the county of Orange and State 5 of Florida, have invented a new and useful Wagon Running-Gear, of which the following is a specification.

The invention relates to improvements in running-gear.

10 The object of the present invention is to simplify and increase the durability, neatness, and lightness of running-gear, and to dispense with the ordinary construction of hounds.

The invention consists in the construction 15 and novel combination and arrangement of parts hereinafter fully described, illustrated in the accompanying drawings, and pointed out in the claims hereto appended.

In the drawings: Figure 1 is a perspective 20 view of a portion of a running-gear embodying the invention. Fig. 2 is a longitudinal sectional view.

Similar numerals of reference indicate corresponding parts in both figures of the drawings.

25 1 designates a front axle of a running-gear, having mounted on it an axle-bed 2, which is provided with a central extension 3, and which has in the latter a horizontally-elongated opening 4. A reach 5 has its front end pivoted by a king-bolt 6 in the opening 4 of the extension of the axle-bed, and a rocking bolster 8 is arranged directly upon the extension of the axle-bed, thereby dispensing with the ordinary sand bolster. The reach is supported by upper and lower rectangular horizontally-disposed frames 9 and 10, constructed of metal and extending rearwardly from the axle-bed and having the front ends of their sides bent 30 downward and secured, by bolts, to the axle-bed. The horizontal frames form simple, light, strong and durable supports for the reach, and their depending ends 11 provide securing plates, and they greatly increase the neatness and beauty of the running-gears of vehicles, and dispense with the ordinary construction of hounds, and also cheapen the construction. The outer portions of the horizontal frames are spaced by vertical sleeves 35 12, which are secured in position by bolts 13,

and the latter also serve to secure the rear upper ends of inclined braces 14 to the lower frame. The lower front ends of the inclined braces are secured to the axle by bolts 15, which pass through the axle, axle-bed, and 55 the lower one of a pair of plates 16, which are interposed between the axle-bed and bolster.

It will be readily seen that the supporting frames increase the lightness, strength and durability of running-gears, that they dispense with the ordinary construction of hounds, that they cheapen the construction, and may be readily applied to a running-gear. It will also be seen that by extending the axle-bed and arranging the parts as shown, the ordinary sand bolster is dispensed with.

Changes in the form, proportion, and the minor details of construction may be resorted to without departing from the principle or sacrificing any of the advantages of this invention.

What I claim is—

1. In a running-gear, the combination with a front axle, of upper and lower horizontal frames extending rearwardly therefrom and connected therewith, and a reach pivotally connected with the front axle and arranged between the horizontal frames and supported by them, substantially as described.

2. The combination with a running-gear, of horizontally-disposed frames extending rearward from the front axle and connected therewith and arranged parallel with each other, spacing sleeves interposed between the rear portions of the frames, and inclined braces 75 extending upward and rearward from the front axle and secured to the rear portion of the lower frame, substantially as described.

3. The combination with a running-gear, of horizontally-disposed rectangular frames having their front ends bent at an angle to form securing plates and extending rearward from the front axle, spacing sleeves interposed between the rear portions of the frames, bolts securing the sleeves in position, and upwardly 80 and rearwardly inclined braces extending from the front axle and secured to the lower frame by said bolts, substantially as described.

4. In a running-gear, the combination of a front axle, an axle-bed mounted thereon and 85 100

having a central upward extension provided with a horizontally-elongated opening, parallel horizontally-disposed upper and lower supporting frames extending rearward from the axle-bed, a reach arranged between the frames, a king-bolt pivoting the reach in the said opening, and inclined braces supporting said frames, substantially as described.

In testimony that I claim the foregoing as my own I have hereto affixed my signature in the presence of two witnesses.

EDWARD E. HENDERSON.
